United States Patent Office

Des. 194,078
Patented Nov. 13, 1962

194,078

COMBINED CAMERA AND SUPPORT THEREFOR

Zoltan Takats, Vestal, N.Y., assignor to General Aniline
& Film Corporation, New York, N.Y., a corporation of Delaware

Filed July 6, 1961, Ser. No. 65,821

Term of patent 14 years

(Cl. D61—1)

FIG. 1

Des. 194,078

FIG.3

FIG. 1 is a front perspective view of the combined camera and support therefor showing my new design;

FIG. 2 is a rear perspective view, thereof;

FIG. 3 is a side elevational view thereof.

I claim:

The ornamental design for a combined camera and support therefor, substantially as shown and described.
